WOOL DUSTER

Winfred W. Windle, Millbury, Mass.

Application June 3, 1938, Serial No. 211,639

10 Claims. (Cl. 19—90)

This invention relates to a machine for separating dust and extraneous matters from wool, cotton and other fibres, whether in loose or manufactured form. It may be applied for the dusting of dirt and carbonized cotton from woolen rags or for dusting out foreign material from cotton. It is intended to remove burrs, vegetable fibre and some grease as well as to break up clods in wool or carbonized materials, carbonized vegetable matter, etc.

The principal objects of the invention are to provide a duster with means, operating after the beating cylinder has removed the dust and the like from the fibre, for causing the fibre, with any undetached particles, to come in contact with with blades so located as to further remove the undetached particles; to provide these blades in a form and location in which the descending current of useful fibre and other materials will engage them and separate the coarse heavy materials from the light ones and deposit them in different positions on the screen; to provide means whereby descending fibre and loosened particles will be progressed along the rotating screen with relation to the relative cleanliness of the fibre coming in contact with the blades; and to provide an improved means for introducing the unseparated material to the beater cylinder.

Other objects and advantages of the invention will appear hereinafter.

Reference is to be had to the accompanying drawings, in which

Fig. 1 is a transverse sectional view of a preferred embodiment of this invention; and

Fig. 2 is a side view with parts broken away to show interior construction.

The machine is shown as set up in a hopper 10, which may or may not have a cover over the top. The principal feature for separating the fibre from the loose material is a rotary wire screen cylinder, constituting a cage for the material and a wire screen for allowing the particles separated from the fibre to pass down through it into the hopper. This hopper is provided with a pair of shafts 14 carrying rolls 15 which engage cylindrical bands of metal on the outside of the cylinder to support it and also to rotate it. The fibre is fed into the cylinder through any kind of a feed, as for example, an endless belt 16 at the bottom thereof and preferably near the center of the bottom surface of the cylinder. The cylinder is rotated by the rolls 15 in the direction of the arrow and carries the raw material up one side to a point where it will drop therefrom on a feed apron 17 which, in this case, is carried by three

rolls 18. The upper strand of this feed apron is shown substantially horizontal and it extends over one of the rolls 18 and under a pressure roll 19 against the arms 20 on the beater cylinder 21 which is rotated at a comparatively high rate.

The arms 20 throw the raw material upwardly against a stationary iron cover 22 which is made with surfaces at varying angles so that the material will engage these surfaces with some force, which constitutes the first separating action and detaches much of the foreign material from the fibre. As will be seen, the several arms or vanes 20 will engage the fibre more than once during a single rotation of the beater cylinder and force the materials against this iron cover in various directions. The iron cover and pressure roll 19 are protected at the top by two partitions 23 which are in stationary position. One of these partitions or walls 23 on the left constitutes an inclined surface to bring down back on the apron 17 by gravity any materials that fall upon it.

A cylinder 24 with radial arms 25 at the top of the cylinder rotates in the direction of the arrow and keeps this screen cylinder from carrying the fibre all the way around and forces the fibres 25 of the raw material back against the inclined surface 23 or on the apron 17 so that practically all of the material introduced into the screen cylinder has to go through the action of the beater cylinder. The beater cylinder is located above a metal draft cutoff 26 to protect the material from dropping from it directly on the screen. Any material that drops on this cutoff will be brought back again by the arms 20 on the beater 21 so as to go through the necessary process.

At the right of the beater cylinder and of the iron cover 22 is a stationary iron plate 28. There is located at the end of it, over the iron plate, a bar 29 which is adjustable back and forth. It is also pivotally connected with a series of blades 30, each one of which is shown as curved at the bottom and as flaring out on a curve through a comparatively wide surface. By moving this bar 29 horizontally the blades 30, which are arranged in parallel condition, can be adjusted on pivots 31 carried by the iron plate to bring them to the desired position to treat the kind of material used. This constitutes the far side through which the fibre and impurities pass. These blades are adjusted in stationary position to receive the lighter material and deflect it forward to fall on the screen in a certain position. The heavy material that falls between the blades, drops straight down to the screen in a position separated therefrom backwardly.

The other side of the course through which these particles pass is bounded by the edges of the cutoff 26 and by a stationary iron plate 32. The iron plates 28 and 32 extend the length of 5 the main cylinder. Pivoted at points 33 on the plate 32 are blades 34, preferably, equal to the number of blades 30 and alternate with them. These blades 34 are adjustable about the pivots 33 by a longitudinal bar 35 which is pivoted to all 10 of the blades 34 near the bottom by a series of pivots 36. These pivots are carried by a series of concave guides 37. The blades also are adjusted to the desired angle and fastened there. They receive the lightest particles and deposit them in 15 a third spot on the screen. Thus, instead of the light and heavy particles being deposited in one spot on the rotary screen, they are deposited in three as shown in Fig. 1. The coarse material is dropped at the first point on the right, coming 20 down between the blades 30. The second pile of fibres indicated is acted on by the blades 30 and moved forward. The finest material is engaged by the blades 34 and dropped. Of course, this figure represents the material at one instant as 25 if the screen had stopped, so it is a little distorted. Thus the finer clean, material will be advanced forwardly more rapidly thru the machine than the heavier, dirty, particles, and the latter are therefore acted upon by the beater more times, 30 resulting in uniformity of the material as it passes from the dusting machine.

By the time the fibre and impurities reach the bottom of the screen cylinder they are thoroughly separated but the fibres, of course, cannot pass 35 through the screen. The impurities are generally small enough so that they will pass through and the impurities fall into the bottom of the hopper 10. At that point they are taken by a suction fan 38 and discharged from the machine, 40 as through a pipe 39, to some point from which they are removed. Any impurities that do not pass through the screen are, of course, brought up in the same way as the original material to a point over the belt 17 and pass through the machine enough times to disintegrate them into 45 smaller particles to be discharged.

By this means the material is brought in at a convenient point, treated one or more times to the action of the beater cylinder and the blades. 50 The fibre is discharged at the other end while the waste is discharged, as described.

Having thus described my invention and the advantages thereof, I do not wish to be limited to the details herein disclosed, otherwise than as 55 set forth in the claims, but what I claim is:

1. In a fibre dusting machine, the combination with a screen cylinder, of means for rotating said cylinder constantly, means for introducing the raw material into the cylinder at one end near 60 the bottom thereof, where it will be taken upwardly by the rotation of the cylinder, an endless apron in the cylinder on which the material is deposited by the cylinder, a pressure roll in the cylinder for compacting the material slightly on the apron, a beater cylinder located at a point in the screen cylinder from which it receives the material from said apron, and a cover over the beater cylinder inside the screen cylinder having surfaces at varying angles for receiving the impact of the material as it is thrown 65 up by the beater cylinder.

2. In a fibre dusting machine, the combination with a screen cylinder, of means for rotating said cylinder constantly, means for introducing the raw material into the cylinder at one end near 70

the bottom thereof, where it will be taken upwardly by the rotation of the cylinder which is comparatively slow, means in the cylinder on which the material is deposited from the upwardly traveling side of the cylinder, a beater cylinder located at a point in the cylinder from which it receives the material from said means, a cover in the screen cylinder over the beater cylinder for receiving the impact of the material as it is thrown up by the beater cylinder, and a series of 10 blades so located below the beater cylinder as to receive the material discharged therefrom and discharging it at different circumferential points on the bottom of the screen cylinder. 15

3. In a fibre dusting machine, the combination with a rotatable screen cylinder, an apron therein on which the material is deposited by the cylinder, a beater cylinder located at a point in said cylinder from which it receives the material from said apron, a cover in the cylinder directly over the beater cylinder for receiving the impact of the material as it is thrown up by the beater cylinder, and two series of blades located in the screen cylinder below the beater cylinder and providing, between them, a passage for the material discharged from the beater cylinder. 20

4. The combination with a rotatable cylinder screen for receiving fibre, of a beater cylinder therein in position for receiving the fibre therefrom and separating foreign materials therefrom, 30 a pair of series of pivoted blades located in the screen cylinder under the beater cylinder in position to receive between the two series the discharge from the beater cylinder, and means for adjusting each set of blades separately on axes 35 transverse to the axis of the beater cylinder.

5. The combination with a rotatable cylinder screen for receiving fibre, of a beater cylinder therein in position for receiving the fibre and separating foreign materials therefrom, a series 40 of pivoted blades, one series located under the beater cylinder and the other at its side in the screen in position to receive the discharge from the beater cylinder, and means for adjusting all of said blades to any desired point. 45

6. In a fibre dusting machine, the combination with a rotary cylinder, an endless feed belt therein, and a beater cylinder in the cylinder in position to take the material from the belt and disperse it by centrifugal action, of a series of stationary blades arranged at an angle to the direction of travel of the material in the cylinder and spaced apart, to provide spaces through which the heavier material may drop vertically downward to a point on the bottom of the screen, the 55 slanting blades serving to deflect the lighter material forward and deposit them on the bottom of the screen at a different point.

7. In a fibre dusting machine, the combination with a rotary screen, of two series of parallel 60 spaced stationary upright blades therein, one series being located forward of the other and means for delivering fibrous material against them at the top thereof, whereby the heavier particles of said material may drop vertically between them 65 on the lower surface of the screen, said blades having a slanting direction transverse of the screen to engage the lighter material and move it, in dropping, forward with respect to the screen. 70

8. In a fibre dusting machine, the combination with a rotary screen cylinder and a beater cylinder therein in position to take the material and disperse it by centrifugal action, of a series of stationary blades in the cylinder arranged at an 75

angle to the direction of travel of the material and spaced apart, to provide spaces through which the heavier material may drop vertically downward on the bottom of the screen, the 5 slanting blades serving to deflect the lighter particles forward and deposit them on the bottom of the screen at a different point, and a second set of stationary spaced angularly located blades for engaging the still lighter material and depositing it in a third spot.

9. In a fibre dusting machine, the combination with a rotary screen, of a series of parallel spaced stationary upright blades therein, and means for delivering fibrous material against 15 them at the top thereof, whereby the heavier particles of said material may drop vertically between them on the lower surface of the screen, said blades having a slanting direction to engage the lighter material and move it, in dropping,

forward with respect to the screen, and a second set of stationary spaced angularly located blades for engaging the still lighter material and depositing it in a third spot.

10. In a fibre dusting machine, the combination of a rotary cylinder, means to feed fibre particles into the cylinder, and a rotary beater therein to centrifugally separate relatively light and heavy particles, with means feeding the light particles thru the cylinder, while retaining the 10 heavier particles in substantially initial position longitudinally of the cylinder, said means feeding the light particles comprising a series of blades curved forwardly in the direction of feed, each of said blades being adjustably supported at one end and widely flaring from said one end towards its free end. 15
